UNITED STATES PATENT OFFICE.

STILLMAN SHAW, OF FARMINGTON, CONNECTICUT, ASSIGNOR TO THE JOHNS-PRATT COMPANY, OF HARTFORD, CONNECTICUT, A CORPORATION OF CONNECTICUT.

SCREW-PLUG FUSE.

Application filed June 28, 1923. Serial No. 648,200.

To all whom it may concern:

Be it known that I, STILLMAN SHAW, a citizen of the United States, residing at Farmington, in the county of Hartford and State 5 of Connecticut, have invented a new and useful Improvement in Screw-Plug Fuses, of which the following is a specification.

This invention relates to renewable screw plug fuses, that is, those which are so constructed that a new fusible link can be substituted for one that has been blown.

The object of the invention is to provide a construction for fuses of this class which is simple and cheap to manufacture and assemble, which is easy to disassemble and reassemble for substituting a fresh fuse for one that has been destroyed, and which will meet all of the conditions as to safety and reliability required of the standard screw plug 20 fuse.

In the accompanying drawings Fig. 1 shows a side elevation of a plug fuse constructed according to the invention. Fig. 2 is a view looking at the bottom of the same. 25 Fig. 3 is a longitudinal section on one plane. Fig. 4 is a longitudinal section on a plane at ninety degrees to that of Fig. 3. Fig. 5 is a perspective view of the removable link carrier.

30 The chambered body 1 of the plug is desirably made of porcelain, although it may be made of other insulating material if desired. The exterior of the cylindrical body is provided with a thread and fitted to screw on and off this thread is the ordinary threaded metallic ring 2 which forms one of the electrical terminals of the plug. Usually 35 these plugs have a transparent disk 3 covering the open end of the chamber in the plug so that the condition of the link in the interior may be clearly observed.

In the embodiment of the invention illustrated the bottom or closed end of the plug is mortised so as to provide a diametrical slot 4 through the closed end of the plug 40 into the chamber. The fuse carrier 5 is a thin block or flat piece of thick sheet insulating material shaped to fit the mortise so that it may be easily inserted in or removed from 45 position therein when the metallic threaded ring is unscrewed from the body. The carrier illustrated has two outwardly extending wings 6 adapted to rest upon the edges of the body when the carrier is inserted in the mortise, two upwardly extending teats 7 adapted

to project through the slot into the chamber in the body, and a downwardly extending boss 8 designed to project between and a little below the bosses 9 on the end of the body at the sides of the mortise. 60

The fusible element 10 is shown as a flat link cut from sheet metal, as zinc, but it may be a round wire, if desired. One end of the link is folded around the under edge at the middle of the boss 8 of the carrier and the other end of the link is folded around the side edge of one of the wings 6, the intermediate section of the link being looped up over one of the teats 7. When the carrier provided with the link attached in this manner is inserted into the mortise in the end of the body the loop of the link extends upward to the vicinity of the window that closes the chamber. The end of the link that is folded around the boss forms the central electrical contact of the plug while the end of the link that is folded around the wing is in position to be engaged by and make electrical contact with the threaded metallic ring. When the ring is screwed onto the body of the plug the flange 11 at its lower end fits over the wings of the carrier so as to hold it in place, the flange of the ring at the same time engaging the end of the link at the side of the carrier. 70 Notches 12 may be made in the edges of the boss 8 so that the carrier may be conveniently grasped and removed from the mortise when the threaded ring is unscrewed from the body of the plug. 80

The mortise in the end of the body of this plug is readily formed and the carrier is of simple shape and cheaply made. It is an easy operation to bend the ends of the fusible link about the carrier so that one end provides the central electrical terminal and the other end completes the circuit through the metallic threaded ring, while the loop is of sufficient length and so spread that the link will properly function and there will be no danger of establishing a destructive arc when the fuse blows. 90 95

The invention claimed is:—

1. A plug fuse comprising a chambered body of insulation having a threaded exterior and a slot through its bottom end, a link carrier of insulation loosely extending through said slot, a fusible link with one end bent over the bottom edge at the center of the carrier and its other end bent around one of the side edges of the carrier, and a

- threaded metallic ring removably screwed upon the body and electrically engaging with the link and retaining the carrier in position.
5. A plug fuse comprising a chambered body of insulation having a threaded exterior and a mortise extending across the bottom end of the chamber, a flat block of insulation fitting said mortise, a flat fusible link with one end bent around the bottom edge and its other end bent around one side edge of said block, and a threaded metallic ring removably screwed upon and holding said block in position, said ring being in electrical engagement with an end of the fusible link. 50
6. A plug fuse comprising a chambered body of insulation having an exterior thread and a slot through its bottom end, a transparent disk covering the top of the chamber, a link carrier of insulation loosely occupying said slot, a fusible link with one end bent around the bottom at the center of said carrier and its other end bent over one of the side edges of the carrier, and a threaded metallic ring removably screwed upon the body and electrically engaging with an end of said link. 60
7. A plug fuse comprising a chambered body of insulation having a threaded exterior and a mortise extending across the bottom end of the chamber, a link carrier of insulation having a downwardly extending boss and outwardly extending wings loosely fitting said mortise, a fusible link with one end bent around said boss and its other end bent around one of said wings, and a threaded metallic ring removably screwed upon the body and engaging said wings for holding the carrier in place, said ring being in electrical engagement with the fusible link. 70
8. A plug fuse comprising a chambered body of insulation having a threaded exterior and a mortise extending across the bottom end of the chamber, a link carrier of insulation having a downwardly extending boss, outwardly extending wings and upwardly extending teats loosely fitting said mortise, and a threaded metallic ring removably screwed upon the body and engaging said wings for holding the carrier in place. 75
9. A plug fuse comprising a chambered body of insulation having a threaded exterior and a slot through its bottom end, a link carrier of insulation loosely fitting said slot, a fusible link with its ends bent about said carrier, one end providing the center contact of the plug, and a threaded metallic ring removably screwed upon the body and engaging the other end of the link and holding the carrier in position. 80
